INVENTOR —

ELIE W. LABOMBARDE.

BY *John Harrison*

ATTORNEY.

UNITED STATES PATENT OFFICE.

ELIE W. LABOMBARDE, OF NASHUA, NEW HAMPSHIRE.

PAPER RECEPTACLE AND METHOD OF MAKING THE SAME.

Application filed January 11, 1923. Serial No. 611,952.

To all whom it may concern:

Be it known that I, ELIE W. LABOMBARDE, of Nashua, in the county of Hillsboro and State of New Hampshire, have invented

5 certain new and useful Improvements in Paper Receptacles and Methods of Making the Same, of which the following is a specification.

This invention relates to boxes, and has 10 particular reference to that type sometimes known as berry boxes or fruit baskets. Such boxes have usually been made of thin wood or veneering which is neither strong nor water-proof. As is well known, the juice 15 or stain of berries readily passes through and escapes from the ordinary berry boxes or fruit baskets.

The object of my invention is to provide 20 a moisture-proof paper box for the above-mentioned uses, which box shall be of low cost and yet very strong.

My invention consists in the box or receptacle, and in the method of making it, substantially as hereinafter described and 25 claimed.

Of the accompanying drawings:—

Figure 1 is a plan view of the preferred form of paper blank, before any folding has been imparted to it.

30 Figure 2 is a perspective view of the box or receptacle in its completely folded and secured condition.

Figure 3 represents a section on the line 3—3 of Figure 2.

35 Similar reference characters indicate similar parts in all of the views.

The blank from which the box or receptacle is made comprises a central rectangular portion 12 which is to form the bottom 40 of the box or basket, the blank being slotted and being also creased as indicated by dotted lines in Figure 1, to form side or wall portions 13, 14, 15, 16. The portions 15 and 16 have flaps 17, extending laterally from the 45 ends thereof, and all of the side or wall portions 13, 14, 15 and 16, have outer narrow extensions as indicated at 18 in Figure 1. Said narrow extensions are all folded over and adhesively secured to the portions from 50 which they extend to constitute reinforced or double-thick edges of the side walls of the box as indicated in Figures 2 and 3.

The wall portions 15, 16, are provided with openings of slot formation as indicated 55 at 19, and the central or bottom portion 12

has a plurality of small holes 20, said openings and holes providing for the ventilation which is desirable in berry boxes and fruit baskets.

As indicated in Figure 1, the blank is 60 creased to provide narrow portions 21 between the portion 12 and the two portions 13 and 14, said narrow portions 21 being between crease lines *a* and *b*, so that when the blank is folded as hereinafter described, 65 the box will have two parallel ribs or legs which will hold the bottom 12 elevated slightly from a shelf or other support for the box and thereby provide for ample ventilation through the holes 20. In this connection it is to be noted that the portions 70 13 and 14 are longer (in the direction away from the portion 12) than the portions 15, 16, by an amount equaling the width of the portions 21. This is to compensate for 75 the amount necessary to provide the ribs or legs when the blank is folded, and ensure equal height of all four walls of the box.

The material of which the blanks are 80 made is cheap paper stock or what is known as paper board. The blanks are cut before receiving any moisture-proofing treatment. In order that the blanks shall be rendered moisture-proof so that, when converted to box or basket form, access of moisture from 85 the outside through the bottom or sides of the box, or leakage of juice of berries or fruit through the bottom or sides, will be prevented, I preferably employ paraffine. I do not limit myself to the use of the 90 particular material known as paraffine, but shall employ that term for convenience of description and not for the purpose of limitation.

The most economical way to make paper 95 boxes from blanks is to fold the blanks with overlapping portions thereof secured together by glue. As will presently be explained, glue is employed in the production of my improved boxes. But since the presence of 100 paraffine on the surface of paper or paper board greatly interferes with glue as an adhesive to reliably secure overlapping portions together, I so treat the blanks, after they are cut and before folding, that they 105 are amply impregnated with paraffine to be moisture-proof and yet have surfaces so free from paraffine that an adhesive such as high grade or pure hide glue, or gelatine, will hold overlapping portions in permanently 110

secured condition. The preferable method by which I accomplish the results stated is as follows:—

The paper board blanks, while flat as indicated in Figure 1, are fed between squeeze rolls which are suitably supplied with melted paraffine, the rolls being so close together as to force the paraffine into the fibers of the paper board below both surfaces thereof and to, at the same time, squeeze off all surplus paraffine and leave both surfaces of the board in glue-holding condition. The treated blanks are then fed onto a carrier such as a travelling apron to enable them to cool. When a blank is to be converted to receptacle form, glue of such character as hereinbefore described is applied to the flaps 17 and to the extensions 18, and to narrow portions in the form of stripes across the wall portions 13, 14, close to the crease lines *b*. In Figure 1 the shading indicates where the glue is applied as just described. Then the portions or extensions 18 are folded in flat onto the wall portions from which they extend and are subjected to pressure to cause them to permanently adhere in the folded condition indicated in Figure 2. Then the two wall portions 13, 14, are folded toward each other on the crease lines *b*, against the central portion 12, and subjected to sufficient pressure to squeeze the narrow stripes of glue near the crease lines *b* onto the portions 21. Next, the wall portions 13, 14, are swung to nearly upright positions, the turning or swinging being on the crease lines *a*, the narrow portions 21 of course turning down and forming rib-shaped legs because they are stuck to the inner areas of the said wall portions. The adhesive securing together of the portions of the walls 13, 14, which form the rib-shaped legs renders said legs permanent so they can not unfold or flatten down. Therefore, since only two of the said walls have the said legs, air can always have free access to the ventilated bottom from either side through spaces the full width of the other two walls 15, 16. After the portions 13, 14, have been turned

or swung up as just described, the other two wall portions 15, 16, are turned up and their glued flaps 17 overlapped upon or onto the outer surfaces of the portions 13, 14, and subjected to pressure to cause them to adhere and remain in the positions shown in Figure 2. The box or receptacle is now complete and ready for any ordinary use, but I may, if desired, add suitable fastenings such as staples indicated at *c* in Figure 2.

As shown by Figures 2 and 3 the folding in of the extensions 18 not only results in reinforcing the upper edges of the walls of the box by making them double-thick, but also causes the extreme edges or tops of the walls to be rounded and smooth. And the reinforcement of the walls 15, 16, above the openings 19, serves to compensate for such weakening of those walls as is caused by the presence of said openings.

It is to be understood that I do not limit myself to the particular shape or proportions of the receptacle or box illustrated by the drawings, as it need not be square nor have the depth or capacity indicated.

Having now described my invention, I claim:—

A paper receptacle comprising a bottom portion having ventilating openings, and four side portions or walls integral with the bottom portion, two of said walls which are opposite each other having ventilating openings, and the other two walls having doubled narrow portions projecting below the ventilated bottom and forming rib-shaped legs, all of said walls having doubled upper edges, the two walls which are provided with ventilating openings having flaps folded over and secured to the outer surfaces of the other two walls above the rib-shaped legs thereof whereby air can have free access to the ventilated bottom from either side below the two ventilated walls the full width of said bottom.

In testimony whereof I have affixed my signature.

ELIE W. LABOMBARDE.
